UNITED STATES PATENT OFFICE.

AUGUST DLOUHY, OF WALLINGFORD, CONNECTICUT, ASSIGNOR TO H. L. JUDD CO.,
OF NEW YORK, N. Y., A CORPORATION OF DELAWARE.

DESIGN FOR A CURTAIN-POLE BRACKET.

Application filed May 13, 1926. Serial No. 17,699. Term of patent 3½ years.

To all whom it may concern:

Be it known that I, AUGUST DLOUHY, a citizen of the United States of America, and a resident of Wallingford, in the county of New Haven and State of Connecticut, United States of America, have invented a new, original, and ornamental Design for a Curtain-Pole Bracket, of which the following is a specification, reference being had to the accompanying drawing, forming part thereof.

Figure 1 is a side elevation of a curtain pole bracket embodying my new design;

Figure 2 is a front elevation of said bracket.

I claim:

The ornamental design for a curtain-pole bracket, as shown.

AUGUST DLOUHY.
